UNITED STATES PATENT OFFICE.

TOM NORTON, OF NEWTOWN, ENGLAND.

VELOCIPED-FRAME.

SPECIFICATION forming part of Letters Patent No. 613,935, dated November 8, 1898.

Application filed December 28, 1897. Serial No. 663,933. (No model.)

To all whom it may concern:

Be it known that I, TOM NORTON, a subject of the Queen of Great Britain, residing at Newtown, in the county of Montgomery, Wales, 5 England, have invented a new and useful Improvement in the Frames of Velocipedes, (for which I have obtained Letters Patent of Great Britain, No. 5,676, bearing date the 13th of March, 1896,) of which the following is a full 10 and complete specification.

This invention relates to an improved frame for rear-driving bicycles and some types of tricycles and other velocipedes; and it consists, essentially, in the use of a double "diagonal," the object being to obtain a strong and rigid frame of the open type suitable for the use of ladies.

In the frames of cycles for the use of ladies it is usual to dispense with the top member of 20 the ordinary diamond frame and to strengthen the front part of the said frame, which then only consists of the diagonal member and the member extending between the pedal-crank-axle bracket and the socket of the steering-head, by means of another member placed 25 over the aforesaid member extending between the pedal-crank-axle bracket and the socket of the steering-head, which auxiliary member is sometimes straight and sometimes curved. 30 Now according to my invention I duplicate the member known as the "diagonal," extending upward from the pedal-crank-axle bracket and usually employed to carry the seat-pillar, and I brace the points of junction 35 of this auxiliary diagonal to the other members by one or more suitable pieces arranged in any convenient manner.

In the accompanying drawings, which show by way of example in diagrammatic form some 40 methods of carrying this invention into practice in bicycle-frames, A designates the socket of the steering-head; B, the usual diagonal extending upward from the pedal-crank-axle bracket; C, the member connecting the pedal-45 crank-axle bracket with the socket of the steering-head; C', the auxiliary members sometimes used to reinforce or stiffen the member C. These members C and C' are arranged in many ways, the most important of which are

illustrated in the accompanying drawings. 50 The arrangement of these members, however, forms no part of this invention.

D designates the members of the lower back fork, and E the members of the upper back fork, forming together the rear part of the 55 frame adapted to receive the driving-wheel, and X designates the auxiliary diagonal, forming the subject of this invention. This auxiliary diagonal may either extend past the member C' and join the member C, as shown 60 by Figure 1, or it may stop at the member C', as shown by Fig. 3. When it extends beyond the member C' and joins the member C, the member C' may stop at the auxiliary diagonal X, as shown by Fig. 2. 65

It will be obvious that this invention may be applied to either the front or the back part of a tandem bicycle or to both parts. Its application to the front part will be apparent from Figs. 1, 2, 3, and 4, showing its application to a single bicycle, while one method of applying it to both the front and the rear part of a tandem is shown by Fig. 5. 70

What I claim, and desire to secure by Letters Patent, is— 75

In a frame for bicycles and other velocipedes, the combination with the socket A of the steering-head, of a member C connecting the said socket with the pedal-crank-axle bracket, of a diagonal member B extending 80 upward from the pedal-crank-axle bracket to carry the seat-pillar, of an auxiliary member C' connecting the socket A of the steering-head with the lower part of the diagonal member B, of members D extending rearward from 85 the pedal-crank-axle bracket forming the lower back fork, of members E connecting the rear ends of the lower back fork with the upper ends of the diagonal member B forming the upper back fork and of an auxiliary 90 diagonal member X connecting the upper end of the diagonal member B with the auxiliary member C' adjacent to the pedal-crank-axle bracket, as and for the purpose set forth.

TOM NORTON.
